US0D1043199S

(12) **United States Design Patent** (10) Patent No.: **US D1,043,199 S**
(45) Date of Patent: ** Sep. 24, 2024

(54) **COAT RACK**

(71) Applicant: **Jie Wang**, Anji County (CN)

(72) Inventor: **Jie Wang**, Anji County (CN)

(**) Term: **15 Years**

(21) Appl. No.: **35/519,832**

(22) Filed: **Jan. 8, 2024**

(80) **Hague Agreement Data**

Int. Filing Date: **Jan. 8, 2024**

Int. Reg. No.: **DM/234476**

Int. Reg. Date: **Jan. 8, 2024**

Int. Reg. Pub. Date: **Jan. 26, 2024**

(51) LOC (14) Cl. **06-04**

(52) U.S. Cl.

USPC **D6/681.2**; D6/681.3
